UNITED STATES PATENT OFFICE.

ALFRED TROG, OF ELBERFELD, GERMANY.

MANUFACTURE OF WALL-PAPER.

977,054.

Specification of Letters Patent. Patented Nov. 29, 1910.

Application filed June 16, 1910. Serial No. 567,304.

To all whom it may concern:

Be it known that I, ALFRED TROG, a subject of the Emperor of Germany, residing in Elberfeld, Germany, have invented certain new and useful Improvements in the Manufacture of Wall-Paper, of which the following is a specification.

This invention relates to a machine for gluing cords on wall paper bands, in which the cords are glued and then guided with the wall paper between a pair of rolls, whereby the cords are connected to the wall paper.

In the accompanying drawing, Figure 1 shows the machine in front elevation and Fig. 2 in plan.

In the machine frame *a* are mounted the rolls *b* and *c*. They are caused to rotate in opposite directions by means of toothed wheels *d* or *e* from the driving spindle *f*. The bearings of the upper roll *c* are adjustably mounted in the machine frame, so that the said roll can be pressed by means of the spindles *g* against the fixed lower roll *b*. The wall paper *h* which rests in bearings and is wound on the machine frame is carried through between these rolls *b* and *c*. It is then drawn off by means of a well known device and suspended for drying. With the wall paper are carried between the rolls the cords *i*. These are unwound from bobbins *k* which are mounted in an interchangeable manner in a frame. They are first guided through a comb *l* in order to arrange them the necessary distance apart. Then they pass between two rolls, the upper one *m* of which is resting in a fixed bearing. The lower roll *n* which is lined or faced with felt, is mounted between the lateral walls of a trough-like glue tank *o*. The said tank is mounted so as to pivot about a spindle *p*, and is adapted to be raised by means

of an eccentric *r* and a crank handle *s*, whereby the roll *n* rotating in the glue, is pressed against the fixed roll *m*. In that way the cords passing between the two rolls are provided with glue. The driving of these two rolls is effected by means of a toothed wheel and chain gear *t*. The cords are then carried in front of bars *v* which can be brought into suitably inclined position relatively to each other by means of pulleys *w*, and which remove the excess of glue from the cords. They pass then, in order to regulate their distance from each other, through another comb *l* and then over a glass rod *x* on to the wall paper carried over the roll *b*, between which latter and the rolls *c*, the cords are pressed on the wall paper.

What I claim as my invention, and desire to secure by Letters Patent is:—

A machine for gluing cords on wall paper, comprising two press rolls, means for pressing the same together, means for rotating them in opposite directions, combs, a glue tank, a gluing roll rotating therein, an abutting roll, means for pressing said gluing roll against the abutting roll, and excess glue removing rods, the cords being passed with the wall paper band through said press rolls after the cords have been guided through said combs, have been glued by the gluing roll, and have had the excess glue removed by being passed over the excess glue removing rods.

In testimony whereof I have signed my name to this specification in the presence of two subscribing witnesses.

ALFRED TROG. [L.S.]
